UNITED STATES PATENT OFFICE.

ALBERT A. HUSEBY, OF CHICAGO, ILLINOIS.

AUTOMATIC STARTING AND STOPPING DEVICE FOR TALKING-MACHINES.

1,394,173.

Specification of Letters Patent.

Patented Oct. 18, 1921.

Application filed July 31, 1920. Serial No. 400,361.

To all whom it may concern:

Be it known that I, ALBERT A. HUSEBY, a citizen of the United States, residing at Chicago, in the county of Cook and State of Illinois, have invented certain new and useful Improvements in Automatic Starting and Stopping Devices for Talking-Machines, of which the following is a specification.

- 10 This invention relates to the art of talking machines, and has reference more particularly to an improved mechanism for automatically starting and stopping the rotation of the turn-table at the beginning and end 15 of the playing of a record. More specifically, the present invention applies to that type of automatic controlling mechanism wherein the control is effected by the swing- 20 ing movements of the tone-arm, and where- 25 in the mechanism can be set, in advance of the playing of a record, so as to arrest the movement of the turn-table at the comple- 30 tion of a record regardless of the length or size of the latter.
- 35 My present invention is designed to per- form the same broad automatic functions as the mechanism disclosed in my former Patent No. 1,289,784, dated December 31, 1918; and consists of certain improvements there- 40 on designed to reduce the number of parts, simplify the mechanism, lessen the space re- 45 quired for the mechanism, and apply the braking effect directly to the rotary turn- 50 table of the machine, instead of to a mov- 55 able element of the motor, as in my former 60 patent.

With this and other objects in view, which will be apparent from the following detailed description of the invention, the latter con- 40 sists of the novel parts and combinations of 45 devices for effecting the purposes of the in- 50 vention substantially as hereinafter de- 55 scribed, and more particularly pointed out 60 as to subject matter and scope in the ap- 65 pended claims.

My invention, its mode and principle of 70 operation, and the advantages inherent 75 thereon, will all be readily understood and 80 appreciated by those skilled in the art from 85 the following description, taken in connec- 90 tion with the accompanying drawings form- 95 ing a part of this specification, in which:-

Figure 1 is a top plan view, showing the 100 relative positions of the parts just before 105 the brake is released by the outward swing 110 of the tone-arm;

Fig. 2 is a similar view, showing the relative positions of the parts just before the 60 brake is applied by the inward swing of the tone-arm at the conclusion of the playing of a record;

Fig. 3 is a bottom plan view, showing the parts in the relative positions which they occupy in Fig. 1;

Fig. 4 is a view in side elevation of the 65 starting and stopping mechanism as viewed from the right of Fig. 1, the supporting plate and turn-table appearing in section;

Fig. 5 is an enlarged vertical section 70 through the friction joint of the catch-operating lever and its pivotal mounting means; and

Fig. 6 is an enlarged detail in horizontal section of the brake-shoe carrier and its im- 75 mediately associated parts.

Referring to the drawings, 5 designates 80 as an entirety the horizontal supporting plate or platform of the machine which, in practice, is mounted at the upper end, and below the lid or cover, of the usual talking machine cabinet (not shown). This plate or platform, as usual, supports the turn-table 6 and tone-arm 7 on its upper side, and the motor and motor winding mechanism (not shown) on its underside. The tone-arm 7 85 is pivotally mounted to swing horizontally about a vertical axis indicated at 8 and communicates with an underlying horn or amplifier, not herein shown since it forms no part of the present invention. 90

Rigidly secured to the tone-arm 7, as by screws 9, (Fig. 2) is a radially extending arm 10 having formed on one edge thereof an extension 11 which has an inclined or oblique outer edge 12 for a purpose herein- 95 after described. In the supporting plate 5 are formed slots 13 and 14, the former lying a short distance forwardly of the base of the tone-arm, and the latter lying sub- 100 stantially opposite one side of the base of the tone-arm. The purpose of these slots will hereinafter appear. Pivotaly mounted on a stud 15 set in the plate 5 is a small plate 16 having an upstanding arm 17 in which is mounted a brake-shoe 18. This 105 brake-shoe is movable into and out of en- 110 gagement with a depending flange 6' on the turn-table under a swinging movement of the brake-shoe carrier 16. In the member 16 is mounted a stud 19 that projects through an arcuate slot 20 in the main plate 5, and pivotally connected to the lower end

of the stud 19 is a rearwardly extending strip or bar 21 underlying the plate 5 and provided at its rear end with a pin 22 that projects upwardly through the slot 14. The 5 bar 21 has a downwardly bent rear end portion 23 (Fig. 4) to which is anchored one end of a tension spring 24, the other end of said spring being anchored to a stirrup 25 which forms a support for the bar 21. 10 It will thus be seen that the spring 24, acting through the bar 21, normally tends to apply the brake-shoe to the rim or flange of the turn-table and thus hold the latter against rotation. The brake-shoe carrier 16 15 is held in idle or release position against the urging of the spring 24 by means of a catch 26, which lies against the periphery of the carrier plate 16, and when the latter is swung to brake release position, as shown 20 in Fig. 2, snaps, under the impulse of a spring, into engagement with a stop shoulder 27 on the periphery of the plate 16. The upstanding catch 26 projects through a slot 28 in the plate 5 and is formed on the free 25 end of one arm 29 of a catch actuating lever. The other arm 30 of this lever extends rearwardly in the direction of the base of the tone-arm and is formed with an upwardly bent free end portion 31 that extends upwardly through the slot 13. Above and extending lengthwise of the arm 30 is another arm 32 that is formed at its free end with a downwardly and rearwardly folded end portion 33 resting on the stirrup 25. 30 This arm 32 is formed with a transverse slot 34 shorter than the slot 13 but registering therewith, the upstanding stud 31 projecting through both slots. The arm 32 constitutes a positioning or setting device 35 for the upstanding member 31 within the limits permitted by the length of the slot 13, as hereinafter more fully described. 40 Referring to Fig. 5, the two arms 29 and 30 of the catch-actuating lever are connected to each other by a friction joint, and these lever arms, together with the arm 32, are mounted on a common pivot bolt 35 set in and depending from the plate 5. Encircling the pivot bolt 35 are inner and outer 45 telescopng sleeves 36 and 37, on the latter of which are pivoted the overlapping inner ends of the lever arms 29 and 30, thin fiber washers 38 being interposed to secure a sufficient friction to insure the release of 50 the catch when the arm 30 is swung in one direction and the engagement of the catch with its coöperating stop shoulder when the lever arm 30 is moved in the opposite direction, but permitting the arm 30 to be moved independently of the arm 29 when 55 positioning the stop pin or lug 31 in determining the point at which the turn-table is to be arrested upon the completion of the playing of a record. 60 The arms 29 and 30 are clamped by the

pivot bolt 35 between a spring washer 39 and a flange 37' on the sleeve 37; and the arm 32 is pivoted with sufficient friction to prevent accidental movement between the flange 37' and a spring washer 40 which 70 lies against the underside of the plate 5.

The catch actuating lever having the friction joint last described, is normally urged in a direction to engage the catch with the 75 brake-shoe carrier by means of a light spring 41 best shown in Fig. 3, said spring exerting a light push on the long arm 30 of the lever and itself being anchored on a laterally projecting arm 42 rigidly secured to the arm 32. The arm 42 is connected by 80 a link 43 to the free end of an arm 44 fastened on the lower end of a vertical shaft 45 journaled in the plate 5 and having on its upper end a turning knob 46.

Briefly describing the operation of the 85 mechanism, the brake shoe is normally held applied, as shown in Fig. 1, to hold the turn-table against rotation. When a record disk has been placed on the turn-table, the tone-arm 7 is swung inwardly to a position where-in the stylus or needle occupies the innermost coil of the record groove, or a position slightly inward of the termination of the record, since the last few coils of the groove are usually blank. Since the arm 10 is rigid 90 with the tone-arm, it simultaneously swings in the same direction. The knob 46 is then turned, thereby swinging the arm 32 toward the arm 10, said arm 32 carrying with it the arm 30 by reason of the engagement of the 95 controlling end of the slot 34 with the up-standing end 31 of the arm 30, until said member 31 strikes the arm 10. This determines the point at which the playing of the record will be arrested. In this movement, 100 the lever arm 30 turns on the friction joint independently of lever arm 29, which cannot partake of the swinging movement because catch 26 lies against the periphery of the brake-shoe carrier. The tone-arm is 105 then swung outwardly somewhat beyond the position at which the stylus will engage with the outermost coil of the record groove, and in so doing the inclined edge 12 of the extension 11 of the arm 10 strikes squarely 110 against the stud 22, this position of the parts being shown in Fig. 1. The forcing of the stud 22 rearwardly exerts a pull on the bar 21, against the tension of spring 24, and rocks the brake-shoe carrier in a direction 115 to release the brake-shoe, as shown in Fig. 2. This rotation of the brake-shoe carrier brings the stop shoulder 27 opposite the catch 26; and the instant this occurs, the spring 41 acts upon the catch actuating lever 120 to throw the catch behind said shoulder, thus locking the brake-shoe in release position. This latter operation shifts the stud 31 a slight distance lengthwise of the slot 34 to 125 about the relative position shown in Fig. 2, 130

which is slightly in advance of the position in which it was manually set. As soon as the playing of the record is completed, the arm 10 strikes the stud 31 and thereby rocks 5 the catch lever, shifting the catch 26 out of engagement with the shoulder 27 of the brake-shoe carrier, and the spring 24, is then free to instantly apply the brake.

In association with the automatic starting 10 and stopping mechanism above described, I have included a simple device by which the brake shoe can be applied and released manually when desired.

Referring to Fig. 6, 47 designates an arm 15 loosely mounted on the bearing hub 48 of the brake-shoe carrier 16, and held in place by a washer 49, (Fig. 4) on the head of the pivot stud 15. In the arm 47 adjacent to its pivot is formed a segmental opening 50 in 20 which projects a small stud 51 on the brake-shoe carrier plate 16. In the opening 50 lies a small coil spring 52 that abuts at one end against the stud 51 and at its other end against the opposite end of the segmental 25 opening. This normally holds the arm 47 in the radial position shown. When it is desired to release the brake, the arm is swung to the left, (Fig. 6) and the brake-shoe carrier is turned in the same direction by reason 30 of the engagement of one end of the opening 50 with the pin 51, until the catch 26 snaps into engagement with the shoulder 27. When it is desired to manually apply the 35 brake, the arm 47 is swung in the reverse direction, compressing spring 52, and a cam edge 47' of the arm forces the catch 26 away from the stop shoulder 27 at once permitting the spring 24 to apply the brake; the 40 spring 52 returning the arm 47 to normal radial position.

It is believed that the construction and operation of the present improvement will be readily understood from the foregoing without further detailed description. Manifestly, the invention may be modified and varied from the precise details herein shown and described without involving any change in its substantial character or sacrificing any of the advantages thereof. Hence, I reserve 45 such variations and modifications as fairly fall within the spirit and purview of the appended claims.

I claim:

1. In an automatic stopping mechanism 55 for talking machines, the combination of a supporting plate, a turn-table above said plate, an arm mounted to swing horizontally above said plate, a brake-shoe carrier pivotally mounted on said plate, a brake-shoe 60 on said carrier movable into and out of engagement with said turn-table, a spring normally urging said brake-shoe into engagement with said turn-table, a lever pivoted

on said plate and having its arms connected to each other by a friction joint, one of said arms carrying at its outer end a catch engageable with said brake-shoe carrier, and the other arm carrying at its outer end an upstanding member located in the path of travel of said first-named arm, a spring acting 65 on said lever to force said catch into engagement with said carrier, an arm pivoted concentric with said lever and having a transversely slotted free end through which said upstanding member projects, and 70 manually operable means for swinging said last-named arm whereby to set said upstanding member at any predetermined point in the path of travel of said first-named arm.

2. In an automatic starting and stopping mechanism for talking machines, the combination of a supporting plate, a turn-table above said plate, an arm mounted to swing horizontally above said plate, a brake-shoe carrier pivotally mounted on 80 said plate, a brake-shoe on said carrier movable into and out of engagement with said turn-table, a spring acting to turn said carrier in a direction to apply said brake-shoe, means actuated by said arm on its outward 85 swing to turn said carrier in opposition to said spring and release said brake-shoe, a spring-pressed catch coöperating with said carrier to hold said brake-shoe in release 90 position, means, including a contact stud 95 located in the path of travel of said arm, to release said catch on the inward swing of said arm, and manually operable means for setting said stud at any predetermined point in the path of travel of said arm. 100

3. In an automatic starting and stopping mechanism for talking machines, the combination of a supporting plate, a turn-table above said plate, an arm mounted to swing horizontally above said plate, a brake-shoe 105 carrier pivotally mounted on said plate, a brake-shoe on said carrier movable into and out of engagement with said turn-table, a spring acting to turn said carrier in a direction to apply said brake-shoe, means connected to said carrier, and including a contact stud located in the path of travel of 110 said arm, and struck by the latter on its outward swing, for turning said carrier in opposition to said spring and releasing said 115 brake-shoe, a spring-pressed catch coöperating with said carrier to hold said brake-shoe in release position, means, including a contact stud located in the path of travel of said arm and struck by the latter on its 120 inward swing, to release said catch, and manually operable means for setting said last-named stud at any predetermined point in the path of travel of said arm.

ALBERT A. HUSEBY.
